HENRI QUIBY, OF ZURICH, SWITZERLAND, ASSIGNOR TO AKTIENGESELLSCHAFT DER MASCHINENFABRIKEN ESCHER WYSS & CIE., OF ZURICH, SWITZERLAND.

GUIDE-WHEEL BLADING FOR ROTARY ENGINES, PARTICULARLY FOR STEAM TURBINES.

Application filed July 1, 1925, Serial No. 40,923, and in Switzerland July 8, 1924.

This invention relates to guide wheel blading for rotary engines and in particular for steam turbines. In a turbine of this class, when the flow of steam from the inlet to the condenser is directed in the main axially or obliquely to the shaft of the turbine, it is desirable to allow the jets of steam to enter each guide wheel as uniformly as possible, that is to say, in the form of a rotary body which has the axis of the turbine as an axis of rotation. All superfluous deflection of the jet of steam, particularly in the vicinity of the outlets of the guide channels should be avoided. These conditions have, in general, not been fulfilled by a long way in guide apparatus as hitherto constructed.

A well known and frequently used form of guide apparatus has a purely cylindrical slot or gap which is divided up by blades into guide passages with apparently straight line guiding walls at the outlet end. This form of guide channel is particularly unsuitable for small diameters because in the most favourable case the steam moves along a helical line. The result of this is that the outer wall of the channel imparts a centripetal acceleration to the particles of steam which results in outward compression, eddies (vortices) and deflection of the jets in a radial direction.

In another type of construction, which is more convenient for the purpose than the one above mentioned, the cross sectional areas of the outlets of the guide channels, which are of rectangular form, are so twisted relatively to each other in the direction of rotation of the rotor wheel, that the jets of steam form approximately a coherent annular surface on their entry into the blading of the rotor wheel. The disadvantage of this form of the guide channels is however that not all the particles of steam are compelled to traverse the same path, the particles of steam flowing along the hollow surfaces of the guide blades having to traverse a longer path than the other particles. The result is eddying and twisting.

According to the present invention, in order therefore to insure the steam being led practically without eddying or twisting and avoid all undesirable deflections, the walls which bound the guide channels radially inwards and outwards are constructed in the guide wheel blading, at least in the

vicinity of the outlets of the guide channels, as single shell hyperboloids with asymptotic cone, the generatrices of which are prescribed straight line paths of flow. In such a construction of the guide wheel blading the whole of the steam jets which strike the rotor on the same circle form a single shell hyperboloid with asymptotic cone.

The parts of the blades which divide up the space between the two single shell hyperboloids may conveniently be constructed with straight lines.

In the accompanying drawings are shown, by way of example, constructional forms of the invention.

Fig. 1^a is a portion of a longitudinal section through a steam turbine having guide wheel bladings according to this invention.

Fig. 1 is a portion of a guide wheel of a steam turbine seen from the outlet side and in which the walls which bound the guide channels radially on the outside are omitted for the sake of clearness.

Fig. 2 is a plan view of Fig. 1.

Fig. 3 is a section on the line III—III of Fig. 2 and

Fig. 4 is a portion of a section on the line IV—IV of Fig. 1 developed in the plane of the drawing.

Fig. 5 is an axial cross-section through a portion of a guide wheel in which the guide blades form a unit with an enclosing ring which bounds the guide channels radially on their outer sides.

Fig. 6 is a section, corresponding to Fig. 5, through a guide wheel with an enclosing ring in which the blades form a unit with a ring which bounds the guide channels radially on their inner sides.

Fig. 7 shows in section, taken at right angles to the axis of the guide wheel, a portion of a guide wheel blading in which the passages are radially bounded on their inner and outer sides by intermediate distance pieces.

Fig. 8 is a section on the line VIII—VIII of Fig. 7.

Fig. 9 shows an axial cross-section through a portion of a guide wheel in which the outlet of the driving medium from the guide channels takes place on the right hand side of the parallel circle containing the axis of the single shell boundary hyperboloid.

Fig. 10 shows a corresponding section through a portion of a guide wheel, in which the outlet takes place on the left hand side of the parallel circle containing the $x-x$ axis.

5 Figs. 11 and 12 show portions of axial cross-sections through two guide wheels in which the outlet mouths of the channels are inclined to the guide wheel axis $y-y$ (shown in Fig. 11 only).

10 Figs. 13, 14 and 15 show in plan and in two axial cross-sections portions of a blading in which each guide channel has, in conjunction with an outlet portion bounded by 15 single shell hyperboloids with asymptotic cone, an inlet portion bounded inwards and outwards (regarded in a radial direction) by surfaces which are not constructed as single shell hyperboloids.

20 In Fig. 1^a are shown two different kinds of guide apparatuses 30 and 31 of a steam turbine. The guide apparatus 30 is fixed to the casing 32 of the turbine and bounds the steam admission chamber 33. The second guide apparatus 31 is disposed between the first rotor-wheel 34 and the second rotor wheel 35. The guide bladings of the apparatus 31 are designed in the manner described later on with reference to Fig. 5, 30 while the guide bladings of the guide wheel 31 are designed in the manner described later on with reference to Fig. 15.

35 Figs. 1 to 4 show a portion of a guide wheel having blades 2 which serve to bound the guide channels laterally. These channels are bounded inwardly (regarded in a radial direction) by a surface 1. The surface 1 and the blades 2 are in this case, cut out of a solid ring 3. According to the invention the inner boundary surface 1 is constructed as a single shell hyperboloid with asymptotic cone, the generatrices of which cone are prescribed straight line paths of flow. The generatrices of the asymptotic cone of the hyperboloid in question form, 40 in the manner shown in Fig. 2, with the parallel circle, which passes through the apex of the shell, an angle α which is equal to the angle of outlet of the steam jets from the guide channels. (By parallel circles is meant the system of circles which yield planes at right angles to the axis of rotation of the single shell hyperboloid.) The surface which bounds the guide channel radially outwards (surface not shown in Figs. 1 to 4) is likewise constructed as a single shell hyperboloid. The generatrices of this hyperboloid are likewise prescribed straight line paths of flow. In a construction of this 45 kind of the surface 1 and of the surface bounding the guide channels radially outwards the propelling medium is compelled to flow in the guide channels along straight line paths, which form the generatrices of the hyperboloids. The blades 2, which con-

55 tain generatrices of the aforesaid single shell hyperboloids, are of rectilinear shape and form a whole with the ring 3. They are cut from a solid ring by imparting to the cutting tool relatively to the blank a straight line movement corresponding to the prescribed straight line path of flow.

60 The bounding of the outer sides of the guide channels (regarded in a radial direction) may be conveniently effected by an enclosing ring the internal surface of which, as already stated, is constructed in the form of a single shell hyperboloid. Such enclosing rings 4 are shown in Figs. 5 and 6, 65 where 5 denotes the surface constructed as 70 a single shell hyperboloid.

75 Instead of constructing the blades 2 in one piece with the inner ring 3, as shown in Figs. 1 and 6, they may be cut out of the enclosing ring so that they are integral 80 therewith in the manner depicted in Fig. 5.

85 The inside and outside bounding of the guide channels in radial direction may also be effected by intermediate distance pieces 6, 7 as shown in Figs. 7 and 8. In this case 90 the blades 8, which bound the guide channels 9 laterally are held fast between the distance pieces 6, 7. The outer peripheral surface 10 of the distance pieces 6 and the inner peripheral surface 11 of the distance 95 pieces 7 are constructed as single shell hyperboloids with asymptotic cone. Such distance pieces 6, 7 may be conveniently cut out of solid rings, after their inner and 100 outer surfaces have been turned in the form of single shell hyperboloids. The fixing of the distance pieces 6, 7 in a guide wheel disc and in an enclosing ring, which may if necessary surround this latter, and the 105 retention in place of the blades may also be effected in a different manner from that shown in Figs. 7 and 8 and described with reference to these figures. Thus, for example, the distance pieces 7 may be connected by welding to the blades 8 and in 110 such case the provision of an enclosing ring is unnecessary.

115 The outlet mouth, that is to say, the cross sectional area of the guide channel outlets may lie in any parallel circle of the single shell hyperboloids, so that the outlet of the steam from the guide channels with respect to a parallel circle which contains the $x-x$ axis of the hyperboloids can therefore take 120 place to the right or left of this parallel circle or in the circle itself. In the guide apparatus shown in Fig. 9, where 3 again denotes the ring which bounds the guide channels on the inside and 4 the enclosing 125 ring, the cross sectional areas 12 of the channel-outlets (only one of which is visible) lie in a section of a circle which lies to the right of the parallel circle with the radius 14, whereas in the guide apparatus shown in Fig. 10 the section of the circle in 130

which the cross sectional area 12 of the outlets lie, lies on the left of the parallel circle with the radius 16.

As shown in Figs. 11 and 12 the outlet parallel circles 19, 20 for the inner and outer single shell hyperboloids 17 and 18 may lie in different planes, so that then the outlet cross-sectional area 21 of each guide channel is made to lie obliquely to the axis $y-y$ of the turbine. In the constructional form shown in Fig. 11 oblique admission inwards takes place and in the constructional form shown in Fig. 12 oblique admission outwards.

In conjunction with a portion of a guide channel bounded inwards and outwards by single shell hyperboloids a portion may also be provided on the inlet side of such a channel which is not bounded by surfaces which are constructed as single shell hyperboloids but as cylindrical surfaces, for example. Such guide channels are shown in Figs. 13 to 15 where 22, 23 are single shell hyperboloids with asymptotic cone, while 24 denotes cylindrical surfaces. The paths of the particles of steam flowing through the guide channels have in these cases, as shown in Fig. 13, a curved portion 25 and a straight portion 26.

I claim:

1. Guide blading for rotary engines particularly for steam turbines, comprising a body having an annular space bounded radially by inner and outer walls, and blades subdividing the space into channels, said walls at least in the vicinity of the outlets of the channels having the shape of single shell hyperboloids having an asymptotic cone and the generatrices of the surfaces of said walls are prescribed straight line paths of flow.

2. Guide blading for rotary engines particularly for steam turbines, comprising a body having an annular space bounded radially by inner and outer walls, and blades subdividing the space into channels, said walls at least in the vicinity of the outlets of the channels having the shape of single shell hyperboloids having an asymptotic

cone and the generatrices of the surfaces of said walls are prescribed straight line paths of flow and the blades between the single shell hyperboloid walls being rectilinear.

3. Guide blading for rotary engines, particularly for steam turbines, comprising a solid ring the outer peripheral surface of which is a single shell hyperboloid with asymptotic cone and the generatrices of which surfaces are prescribed straight line paths of flow, blades cut in said solid ring in straight lines defined by said generatrices and an outer ring surrounding the first mentioned ring and blades and having a similar hyperboloid inner surface.

4. Guide blading for rotary engines, particularly for steam turbines, having an annular space bounded radially by inner and outer walls, and blades subdividing the space into channels, said walls at least at the discharge ends of said channels having the shape of single shell hyperboloids with asymptotic cone, and the generatrices of which are prescribed straight line paths of flow, and said blades being rectilinear between the hyperboloids and the outlets of the channels formed by said blades being at any section of a parallel circle of the hyperboloid.

5. Guide wheel for rotary engines, particularly steam turbines, comprising a disc-shaped body having an annular space bounded radially by inner and outer walls and blades dividing said space into separate channels, said walls, at least at the discharge ends of said channels, having the shape of single shell hyperboloids with asymptotic cone and whose generatrices are prescribed straight line paths of flow, the blades being rectilinear between the hyperboloid walls, said walls terminating at the discharge end of the channels lying in parallel circles in different planes so that the outlet mouths of the channels will lie obliquely to the axis of the disc-shaped body.

In testimony whereof, I have signed my name to this specification.

HENRI QUIBY.
